LEE SUTHERLIN, OF EAST PITTSBURGH, PENNSYLVANIA, ASSIGNOR TO WESTINGHOUSE ELECTRIC & MANUFACTURING COMPANY, A CORPORATION OF PENNSYLVANIA

HOT CATHODE ELECTRON DISCHARGE TUBE

Application filed August 14, 1926. Serial No. 129,121.

My invention relates to hot-cathode-electron-discharge tubes of the type utilizing cathodes in the shape of filamentary ribbons and, among the objects of the invention is 5 the provision of an improved mounting or support for such ribbons, whereby better and more uniform tube operation is obtained.

In many types of radio-receiving tubes designed to give a large output sufficient to operate high-power loud speakers, and the like, 10 it has been found necessary to make the cathode of a looped filamentary ribbon in order to obtain the required electron emission. The plates or anodes of such tubes are usually of oval or rectangular shape with relatively large, flat side surfaces facing the loops of the filaments.

So far as I am aware, heretofore, practically no attention has been given to the way in 20 which the plane of the ribbon filament was related to the adjacent surfaces of the plate, so that, in general, parts of the filament had their edges exposed to the plate surfaces while other parts had their flat sides exposed there- 25 to. It is clear that this haphazard manner of mounting the filament not only affects the uniformity of the tubes so made, but it also is bound to unnecessarily increase the plate impedance, inasmuch as the major portion 30 of the electrons which are emitted from the large flat ribbon surfaces have to take a curved path on their way to the plate.

According to my invention, a better and 35 more uniform tube is provided by taking care that the flat sides of the filamentary ribbon shall be exposed toward the plate surfaces for substantially the entire length thereof.

In the accompanying drawings 40 Figure 1 is an enlarged perspective view of a radio-receiving tube with parts of the envelope and the electrode structure broken away to show the improved electrode support,

Fig. 2 is a vertical sectional view through 45 the electrode assembly of Fig. 1 along the line II-II,

Fig. 3 is a view similar to Fig. 1 showing a modified filament support.

Fig. 4 is a detail view of the filament and 50 supports of the Fig. 1 modification.

Fig. 5 is a horizontal cross-sectional view on line V-V of Fig. 1.

Referring to Figs. 1, 2 and 4 of the drawings, which show a preferred embodiment of my invention, a radio-receiving tube comprises a glass envelope 1 having, at its bottom, a re-entrant stem 2 terminating in a flat press 3, into which are fused a plurality of lead-in and supporting wires referred to hereinafter. 55

Directly above the press 3 and substantially in the same plane therewith, is mounted a cathode in the form of an inverted W-shaped ribbon 5, the two upper lights thereof being supported by a pair of spring hooks 6 which are secured to a pair of supporting rods 7 which are held in spaced relation by a glass bead 8 that is fused around the upper end of a carrier rod 9, the lower end of which is offset and fused into the center of the press. 60

The support for the two ends of the filament and the electrical connection for sending current therethrough is provided by a pair of lead-in wires 11 fused into the press on both sides of the central carrier rod 9, 75 the upper ends of the lead-in wires being bent outwardly to terminate approximately at the points where the ends of the filament are to be held. The lower middle bight of the filament is held by an additional hook 12, which is secured to the offset carrier rod 9 near its lower end, where it is fused into the press 3. 80

The two loops of the W-shape cathode filament 5 are surrounded by an oval-shape 85 plate or anode 15 having extended flat sides 16 which are substantially parallel to the plane of the filament loops.

In spaced relation from the filament loops 5 and the plate 15 and interposed there- 90 between, is a grid helix 17 which is of oval shape, conforming substantially to the shape of the plate 15.

The plate 15 and the grid 17, in the interior thereof, are insulatingly supported and spaced by means of two pairs of supporting wires 18 and 19, respectively, the left-hand anode-supporting wire and the right-hand grid-supporting wire constituting also the lead-in connections thereto, respectively. 95

As stated above, I have found that the performance of the tube will vary within relatively wide limits, depending on whether the edge or the flat side of the filamentary cathode ribbon is exposed to the adjacent anode surfaces. Accordingly, the tubes of the above-described character, as manufactured heretofore, varied greatly in their characteristics, a fact which greatly perplexed those responsible for the design and manufacture of such tubes.

According to my invention, not only the undesirable discrepancies in the characteristics of such tubes are avoided, but also the tube performance is greatly improved by so arranging the support of the filament loops that they are disposed throughout the entire active lengths with their flat sides facing the adjacent flat plate surfaces.

The actual structural changes necessary to obtain the improved cathode mounting are very small, although, as pointed out above, the resulting effect is very material. Thus, in the prior-art tubes, the two extreme ends of the W-shaped filament ribbon were secured or fastened to the outwardly bent ends of the lead-in wires 11 in substantially the same way as is shown in the drawings, that is, with the flat sides of the ribbon disposed parallel to the flat sides of the anode.

The plane of the hooks 6 and 12, which support the upper and lower bights of the filament, in the prior art tubes, were usually perpendicular to the plane of the filament loops, so that the middle V of the filament loop had its edges exposed toward the adjacent sides of the plate while the two upper ends of the loop were disposed edgewise and their lower ends were disposed flatwise with respect to the plate surface. All that was necessary to obtain the improved mounting of the filament, as described hereinbefore, was to change the plane of the hooks 6 and 12 which support the upper and lower bights of the filament loop.

To this end, the hook portion 20 at the end of the upper hook 6 of the prior-art hook has been turned 90° sidewise so that the hook, as shown in the drawings, now lies in the plane of the filament loops. Similarly, the hook 12, which holds the lower bight of the filament is now mounted in the plane of the filament loop. With the changed location of the planes of the hooks, the filament ribbon 5 is now wound so that the edges of the filament are always disposed in the direction of the filament loop while the flat sides are exposed toward the flat sides of the plate surfaces on both sides thereof.

It is, of course, clear that my invention is not restricted to the particular arrangement and details of construction shown in the preferred embodiment described above.

One of the ideas underlying my invention, namely, the means of ensuring tubes of uni-

form characteristics may, for instance, be applied without, at the same time, applying the idea of securing lower plate impedance. A tube of such construction would merely have the filament wound edgewise perpendicularly to the plane of the filament loops throughout its entire length. In such case, the plane of the filament hooks will be the same as described hereinabove in connection with the prior-art tubes, the only change required being to turn the plane in which the two extreme ends of the filament ribbon are supported on the lead-in wires 11. Such an arrangement of filament support is shown in Fig. 3 of the drawings. Many other modifications of my invention will readily suggest themselves to those skilled in the art.

I claim as my invention:

1. In an electron-discharge tube, a ribbon-shape filament, an anode having substantially plane, active surfaces spaced apart by a distance greater than the width of said ribbon, the anode enclosing said filament being so supported that the flat sides thereof are exposed to the surface of said anode throughout substantially the entire active length of said filament. 85

2. In a hot-cathode-electron-discharge tube, a filamentary cathode ribbon, a tubular anode surrounding said ribbon and having opposing flat faces separated by a distance greater than the width of said ribbon, and means for so supporting said cathode ribbon that the flat sides thereof are exposed to and parallel with said flat faces of the anode. 95

3. In a hot-cathode-electron-discharge tube, a filamentary cathode ribbon, a tubular anode surrounding said ribbon and having narrow and wide sides corresponding substantially in configuration to the edge and flat sides of the ribbon, its narrow sides being greater than the width of said ribbon, and means for so supporting said cathode ribbon that its flat sides are exposed throughout substantially their entire active length parallel to the wide sides of said anode. 100

4. In a hot-cathode-electron-discharge tube, an anode comprising a member having substantially flat extended-surface portions, a filamentary cathode ribbon constituting a loop in a plane parallel to said flat anode surfaces, and means for so supporting said loop that the flat sides of the ribbon are exposed throughout substantially their entire active length to the flat surface portions of said anode. 110

5. In a hot-cathode-electron-discharge tube, a substantially flattened tubular anode member having relatively large parallel opposing active surface portions, a filamentary cathode ribbon constituting a loop disposed in a plane substantially midway between said parallel-surface portions, and means for so supporting said filament that the flat sides 125

thereof lie in planes parallel to the plane of the loop.

6. In an electron-discharge tube, a tubular flat anode, a filament ribbon constituting a loop disposed in a central plane within said anode parallel to the flat sides thereof, means for supporting the upper bight of said loop comprising a carrier rod extending outside said anode, a spring arm supported by said carrier rod and extending to above said bight
10 the end of said spring arm constituting a hook for supporting the filament bight, said hook being disposed substantially in the plane of said loop, and means for so supporting the lower ends of said filament that the
15 flat sides thereof are parallel to the plane of the loop.

7. In an electron-discharge tube, an inverted V-shaped loop of a filamentary cathode ribbon having flat sides held with its flat
20 sides substantially in a plane, a tubular anode having flattened sides surrounding said cathode ribbon and having said sides parallel to said plane.

8. In a hot - cathode - electron - discharge device, a cathode comprising a filamentary ribbon so flatwise folded upon itself that the two legs diverge and constitute a substantially V-shape loop lying substantially in the plane of the flat ribbon sides.

25 9. In a hot - cathode - electron - discharge device, a cathode comprising a filamentary ribbon so flatwise folded upon itself that the two legs diverge and constitute a substantially V-shape loop, and a wire portion so supporting the fold of said ribbon that the two ribbon sides lie flat in the plane of the loop.

30 In testimony whereof, I have hereunto subscribed my name this 11th day of August, 1926.

40 LEE SUTHERLIN.
